Primary Examiner—Louis S. Zarfas*Assistant Examiner*—G Andoll*Attorney, Agent, or Firm*—Charles N. Quinn, Esq.[57] **CLAIM**

The ornamental design for a therapeutic post-operative leg elevator, as shown and described.

DESCRIPTION

FIG. 1 is a left side elevation of a therapeutic post-operative leg elevator, manifesting the preferred embodiment of my invention.

FIG. 2 is a top plan view of a therapeutic post-operative leg elevator, manifesting the preferred embodiment of my invention illustrated in FIG. 1.

FIG. 3 is a bottom plan view of a therapeutic post-operative leg elevator, manifesting the preferred embodiment of my invention shown in FIGS. 1 and 2.

FIG. 4 is a front elevation of a therapeutic post-operative leg elevator manifesting the preferred embodiment of my invention shown in FIGS. 1, 2 and 3.

FIG. 5 is a rear elevation of a therapeutic post-operative leg elevator manifesting the preferred embodiment of my invention shown in FIGS. 1, 2, 3 and 4.

FIG. 6 is an isometric view of a therapeutic post-operative leg elevator manifesting the preferred embodiment of my invention shown in FIGS. 1, 2, 3, 4 and 5, taken looking at the left side and the front.

The right side of the therapeutic post-operative leg elevator is a mirror image of the left side illustrated in FIG. 1.

The broken lines in FIG. 1 is for illustrative purposes only and forms no part of the claimed design.
